Bowser, Jr., University City, Mo.

Application February 18, 1948, Serial No. 9,086

15 Claims. (Cl. 309—10)

1

This invention pertains to pistons such as the light-metal pistons used in internal-combustion engines for automobiles and the like.

Among other tendencies in the modern design of such engines one development has tended to increase the stroke of the piston. The consequences of such increase, where it is desired to avoid increase in the over-all dimensions of the engine, may include shortening the piston and increasing the angularity of the connecting rod. Each of these changes increases the tendency of the piston to rock in the cylinder about the wrist-pin axis.

One of the objects of this invention is to provide an improved piston having increased stability against such tendency to rock, and improved control of the fit of the piston in the cylinder.

Further objects will appear from the following description, taken in connection with the accompanying drawings, in which will be set forth an illustrative embodiment of this invention. It is to be understood, however, that this invention is susceptible of various embodiments, within the scope of the appended claims, without departing from the principles or spirit of the invention.

Generally stated, in accordance with this invention, the piston is so proportioned that the cylinder-bearing portion thereof extends well above the wrist-pin axis so that its support by the cylinder wall has increased leverage to resist the tendency to rock. This has been accompanied by shortening of the head portion and relocation of the slot or slots separating the thrust faces of the skirt from the head, and improved means for sealing those slots have been provided.

In the accompanying drawings,

Figure 1 is a side view, along the wrist-pin axis, of a piston embodying this invention, but without the sealing band,

Figure 2 is a half-section on line 2—2 of Figure 1,

Figure 3 is an enlarged, detail section taken on line 3—3 of Figure 2, but with the sealing band in place,

Figure 4 is a transverse section on line 4—4 of Figure 2, also with the sealing band in place, and

Figure 5 includes side and edge views of the sealing band.

Referring to the drawings, 1 designates the skirt portion of the piston. This portion may be "cam ground" so as to be slightly smaller in diameter in the direction along the wrist-pin axis than in the direction transverse thereto. The head portion 2 is defined by being considerably

2

smaller in diameter than the skirt portion 1, so as to allow for maximum thermal expansion thereof without contacting the cylinder wall. Wrist-pin bosses 3 are spaced downward from the upper end of the skirt portion. Between the pin bosses and the upper end of the skirt portion one or more piston-ring grooves 4 may be formed, only one being shown in the embodiment illustrated, leaving, between it and the upper end of the skirt portion a ring land 5 having the same size and shape in cross-section as the skirt portion. Above the ring land 5, the head portion 2 is reduced in diameter as mentioned above to about .020 inch less than the skirt portion 1. This is indicated, to exaggerated scale, at b in Figure 3. The head portion is also provided with one or more piston-ring grooves 6, and the skirt may have a bottom groove 7.

One or both thrust faces 8 of the skirt portion may be separated from the head portion by a horizontal slot or slots 9. This slot should be immediately above the skirt portion. In the embodiment illustrated it is located in the lower-most of the ring grooves 6. One or both thrust faces may also be cut by a vertical slot 10 extending downward from the slot 9 to render the thrust face more flexible.

In order to prevent leakage of the pressure fluid through the slots 9 to the interior of the piston, 30 a sealing band 11 is provided. This may be a simple ring of thin spring steel formed as shown in Figure 5 to a diameter a little less than that of the piston in the bottom of the groove 6. This band is then simply snapped around the piston 35 in the bottom of the groove 6, and so as to cover and seal the slot or slots 9.

The piston, constructed as described above, may be made of a light metal such as aluminum, magnesium, or an alloy thereof, and the dimensions referred to may be adjusted to suit the rate of expansion of the metal used. Thus, the piston, when at its operating temperature, is fitted to the cylinder to provide a bearing thereon which extends well above wrist-pin axis and is, therefore, effective in preventing rocking of the piston about that axis.

In order to control the thermal expansion of the thrust faces, a control element 12 may be provided. This may be made of steel or other material having a rate of thermal expansion less than that of the piston metal, and is located within the piston and anchored to the thrust faces. Many types of control element may be used. In the illustrated embodiment it is oval in shape, and anchored to the middle of one

thrust face, as at 13, and to the lateral portions of the other, as at 14. The action of a control element of this type is disclosed in our co-pending application Serial No. 787,276, filed November 21, 1947. Or it may be anchored at the middle points, as 13, of both faces. The action of such an element is disclosed in our co-pending application Serial No. 719,842 filed January 2, 1947.

It has been found that this invention provides a piston which is relatively stable against rocking about the wrist-pin axis. The skirt portion, extended upward from the wrist-pin bosses, provides a bearing against the cylinder wall above the pin axis effective to counteract the effect of the connecting-rod thrust tending to "tip" the piston about said axis. While the axial length of the head portion may be reduced, the number of piston rings need not be reduced as one or more of them may be placed on the skirt portion. While moving the slot 9 toward the head has placed it in a region of higher pressure of the pressure fluid, the band 11 provides an effective seal against leakage.

Having thus described the invention, what is claimed is:

1. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves, and a control element having a lower rate of thermal expansion than the piston metal connecting said thrust faces adjacent said slot or slots.

2. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves, a control element having a lower rate of thermal expansion than the piston metal connecting said thrust faces adjacent said slot or slots, and means for sealing said slot or slots against leakage of the pressure fluid.

3. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves in the bottom of another of said grooves, and a control element having a lower

rate of thermal expansion than the piston metal connecting said thrust faces adjacent said slot or slots.

4. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves in the bottom of another of said grooves, a control element having a lower rate of thermal expansion than the piston metal connecting said thrust faces adjacent said slot or slots, and means for sealing said slot or slots against the leakage of the pressure fluid.

5. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves in the bottom of another of said grooves, a control element having a lower rate of thermal expansion than the piston metal connecting said thrust faces adjacent said slot or slots, and a sealing band in the bottom of said last groove closing said slot or slots against leakage of the pressure fluid.

6. A light-metal piston of the character described having a skirt portion formed to provide opposite thrust faces and having a piston-ring groove adjacent the upper end thereof, the ring land above said groove being dimensioned to contact the cylinder wall; a head portion having a smaller diameter than said skirt portion and one or more piston-ring grooves formed therein, wrist-pin bosses spaced below said head portion, one or both of said thrust faces being separated from said head portion by a horizontal slot or slots, and a control element having a lower rate of thermal expansion than the piston metal connecting said thrust faces adjacent said slot or slots.

7. A light-metal piston of the character described having a skirt portion formed to provide opposite thrust faces and having a piston-ring groove adjacent the upper end thereof, the ring land above said groove being dimensioned to contact the cylinder wall; a head portion having a smaller diameter than said skirt portion and one or more piston-ring grooves formed therein, wrist-pin bosses spaced below said head portion, one or both of said thrust faces being separated from said head portion by a horizontal slot or slots in one of said ring grooves, means in said last groove for sealing said slot or slots against leakage of the pressure fluid, and a control element having a lower rate of thermal expansion than the piston metal connecting said thrust faces adjacent said slot or slots.

8. A light-metal piston of the character de-

scribed having a skirt portion formed to provide opposite thrust faces and having a piston-ring groove adjacent the upper end thereof, the ring land above said groove being dimensioned to contact the cylinder wall; a head portion having a smaller diameter than said skirt portion and one or more piston-ring grooves formed therein, wrist-pin bosses spaced below said head portion, one or both of said thrust faces being separated from said head portion by a horizontal slot or slots in one of said ring grooves, a sealing band embracing the piston in said last groove to close said slot or slots against leakage of the pressure fluid, and a control element having a lower rate of thermal expansion than the piston metal connecting said thrust faces adjacent said slot or slots.

9. A light-metal piston of the character described having a skirt portion formed to provide opposite thrust faces and having a piston-ring groove adjacent the upper end thereof, the ring land above said groove being dimensioned to contact the cylinder wall, a head portion having a smaller diameter than said skirt portion and one or more piston-ring grooves formed therein, wrist-pin bosses spaced below said head portion, one or both of said thrust faces being separated from said head portion by a horizontal slot or slots in one of said ring grooves, a thin resilient snap-ring in said last groove sealing said slot or slots against leakage of the pressure fluid, and a control element having a lower rate of thermal expansion than the piston metal connecting said thrust faces adjacent said slot or slots.

10. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves.

11. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves, and means for sealing said slot or slots against leakage of the pressure fluid.

12. A light-metal piston of the character de-

scribed having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves in the bottom of another of said grooves.

13. A light-metal piston of the character described having a head portion, a skirt portion formed to provide opposite thrust faces, and pin bosses below said head portion, said head portion having one or more piston-ring grooves therein, said skirt portion having one or more piston-ring grooves therein near the upper end thereof, said skirt portion having a greater diameter than said head portion and the diameter thereof being slightly greater in the thrust axis than in the axis transverse thereto, one or both of said thrust faces being separated from said head portion by a horizontal slot or slots located above one of said piston-ring grooves in the bottom of another of said grooves, and means for sealing said slot or slots against the leakage of the pressure fluid.

14. A light-metal piston of the character described having a skirt portion formed to provide opposite thrust faces and having a piston-ring groove adjacent the upper end thereof, the ring land above said groove being dimensioned to contact the cylinder wall; a head portion having a smaller diameter than said skirt portion and one or more piston-ring grooves formed therein, wrist-pin bosses spaced below said head portion, one or both of said thrust faces being separated from said head portion by a horizontal slot or slots in one of said ring grooves, and means in said last groove for sealing said slot or slots against leakage of the pressure fluid.

15. A light-metal piston of the character described having a skirt portion formed to provide opposite thrust faces and having a piston-ring groove adjacent the upper end thereof, the ring land above said groove being dimensioned to contact the cylinder wall; a head portion having a smaller diameter than said skirt portion and one or more piston-ring grooves formed therein, wrist-pin bosses spaced below said head portion, one or both of said thrust faces being separated from said head portion by a horizontal slot or slots in one of said ring grooves, and a sealing band embracing the piston in said last groove to close said slot or slots against leakage of the pressure fluid.
